John Morgan of Langhorne, in Pennsylvania

Letter Patent.

The subscriber referred to in these letters patent and making part of the same containing a description in the words of the said John Morgan himself of his improvement in spinning wool, Cotton, and other fibrous substances.

To all whom these presents shall come,

Be it known that I, John Morgan of the town of Langhorne in the County of Philadelphia and State of Pennsylvania Cotton Spinner, have invented a new and useful improvement in wool and cotton spinning and other fibrous substances, and that the following is a full and exact description thereof,

1. a spindle, 2. a tube Hollow, 3. two long needles, 4. a fly or flye, 5. a drag. And the following is the manner of using, and the mode in which I contrivanciate the application of that principle or character by which it may be distinguished from other inventions. To wit; The flye is attached to the tube at the bottom under the two long Needles, to which is attached the Drag which may be applied in a variety of ways as follows A leather strap, steel spring, & set screw,

What I claim as my own invention and not previously known in the above described Machine or piece of machinery, is the tube and Drag attached to the flye (see plate Figure 1st,) and which operates by the power of the thread alone. The advantage of this invention are, that in spinning it works with less power makes less waste and more yarn from the same cutting wool, or other fibrous substances.
